UNITED STATES PATENT OFFICE.

JAMES B. BUTLER, OF SAN ANTONIO, TEXAS.

PROCESS OF FORMING INDIVIDUAL FOOT-FORMS AND FITTING SHOES THEREON.

1,372,273.

Specification of Letters Patent. Patented Mar. 22, 1921.

No Drawing.

Application filed October 9, 1919. Serial No. 329,608.

To all whom it may concern:

Be it known that I, JAMES B. BUTLER, a citizen of the United States of America, residing at San Antonio, in the county of Bexar and State of Texas, have invented certain new and useful Improvements in Processes of Forming Individual Foot-Forms and Fitting Shoes Thereon, of which the following is a specification.

10 My invention relates to foot forms and more particularly to a form which will be a replica of an individual foot and to a process of making such replica of each individual foot; and the object is to provide a process for making forms for shaping or setting shoes for individual feet for the purpose of making shoes conform to the shape of the feet without having to break in or set the shoes by wearing the shoes. The advantage is that a person will not have to go through the painful process of breaking in new shoes and the individuals can have the forms made for themselves and retain them or the shoe dealer may make the forms and 20 keep them for preparing the shoes for his customers. Another advantage is that the individual will always get shoes that will fit his feet however ill-shaped or peculiarly shaped the foot may be. Other objects and 25 advantages will be fully explained in the following description and the invention will be more particularly pointed out in the claims.

No drawings are furnished because of the 30 nature of the subject matter. Each individual foot will differ from every other foot in shape or contour and the invention lies more in the process than in any particular shape. The patented devices on the market 35 for stretching shoes stretch the shoes only in a general way, making them somewhat larger all around and not adapting them to the particular shape of the person who is to wear them. My process consists in taking 40 shoes of the person who has worn the shoes until the shoes have become set to the feet of the wearer, filling the shoes with some pliable substance, such as plaster of Paris and the like, which will become hard or firm and 45 retain its shape when it becomes dry, and let the substance dry or become cured in the shoes. After the substance or plastic is dry 50 or cured and hardened, remove the casts from the shoes which have been worn. The

forms are then ready for use at any time. 55 When the new shoes are to be adapted for use by the owner, they are placed on the forms by moistening the leather sufficiently to make the shoes slip on the form and to make the leather conform to the shape of 60 the form. The shoes are left on the forms a sufficient length of time for the shoes to shrink in some places, stretch in other places, and become fixed or fitted to the exact shape of the forms.

65 When the shoes have become set, they are removed from the forms and are ready for wear and may be worn with as much comfort as shoes which have already been worn and set to the feet. Each individual can 70 have its own casts made and set his shoes thereon, or his dealer may have the casts made and set the shoes when his customer orders shoes before he fills the order. It is apparent that this invention cannot be illustrated by drawings, as it would be a rare 75 instance that the casts made for one person would answer the purposes of another person. Consequently the shapes or contours of the casts will differ with different persons. 80 The forms are for individual use. The means for moistening the leather of the shoes for placing the shoes on the casts may be some kind of lubricant or material which will not injure the quality of the leather.

85 What I claim, is,—

1. The herein described process of preparing foot forms and setting shoes which consists in providing shoes that have been worn by an individual, preparing a plastic for 90 filling the worn shoes, curing the plastic in the worn shoes, removing the worn shoes from the plastic, moistening the shoes to be set, and forcing the shoes on the formed casts.

95 2. The herein described process of setting new shoes to the feet of the wearer which consists in selecting a pair of shoes already set to the feet of the individual, preparing a plastic and filling the shoes, curing the 100 plastic in the shoes, removing the worn shoes from the plastic, moistening the new shoes and forcing the same on the formed casts, and removing the new shoes from the casts after the shoes have been set.

105 In testimony whereof, I set my hand, this 29th day of September, 1919.

JAMES B. BUTLER.
